MULTIPLE HOLDER FOR COSMETIC
PREPARATIONS OR THE LIKE

Jan Norriss, New York, N. Y.

Application October 25, 1949, Serial No. 5,691

Term of patent 3½ years

(Cl. D86—10)

To all whom it may concern:

Be it known, that I, Jan Norriss, a citizen of the United States, residing at New York, in the county of New York and State of New York, have invented a new, original, and ornamental Design for a Multiple Holder for Cosmetic Preparations or the like, of which the following is a specification, reference being had to the accompanying drawing, forming part thereof.

Fig. 1 is a front view of a multiple holder for cosmetic preparations or the like, showing my new design.

Fig. 2 is a plan view of Fig. 1.

Fig. 3 is an end view of Fig. 1.

Figs. 4, 5, 6 and 7 are front views of the lipstick, the powder puff, the cap of the powder compartment, and the mascara applicator, respectively.

The back view of the multiple holder is identical to the front view. The lipstick, the powder puff, the cap of the powder compartment, and

the mascara applicator look identically the same from the sides and the back as they look in the front views shown in Figs. 4, 5, 6 and 7, respectively.

I claim:

The ornamental design for a multiple holder for cosmetic preparations or the like, as shown and described.

JAN NORRISS.
